SHOE-TREE

Application filed February 18, 1927. Serial No. 169,249.

This invention relates to shoe trees and is herein illustrated as embodied in a shoe tree constructed largely from moldable sheet material.

5 It has long been understood that simple and practical shoe trees could be constructed by providing a toe piece constructed of moldable sheet material such, for example as celluloid, and combining with this some sort of a heel 55 piece. The heel pieces of such trees have commonly been made of metal to the detriment of the general appearance and utility of the tree.

With this in view, one object of the present 15 invention is to provide an improved shoe tree of simple and relatively inexpensive construction having an attractive and a substantially uniform appearance throughout.

One feature of the invention consists in a 20 shoe tree comprising a toe piece of molded sheet material such as celluloid and a spring metal heel piece connected to the toe piece and provided with a decorative protective cover of flexible, non-oxidizable sheet material 25 similar to the material of the toe piece so that it will blend therewith and thereby not only improve the appearance of the article but also protect the shoe from possible rust on the spring metal.

30 Another feature of the invention relates to a resilient heel piece having a cover of flexible material one end of which is rigidly secured to one end of the heel piece, the cover being slidably secured to the heel piece adjacent to its other end. In the illustrated 35 construction the heel piece is made of resilient strip metal pivotally secured at one end to the toe piece of the tree and curved in the form of a loop at its outer end. A celluloid cover carried around the looped outer end of the heel piece is rigidly attached at its rear end to the strip of metal and is attached at intervals along the length of the heel piece by rivets 40 passing through slots in the cover to allow a slippage between the cover and the metal strip as the latter is flexed. A metal reinforcement, arranged to prevent undue bending of the spring of the heel piece, is attached to the under side of the heel piece by a loosely clenched 45 intermediate rivet.

Still other features of the invention consists in providing, in a shoe tree, a hollow toe piece of resilient material having a rigid bridge member loosely secured to the sides of said toe piece to allow the relative expansion or contraction of the toe piece with respect to the bridge so that the former will be effective in closely engaging the inside of a shoe in which the tree may be inserted.

55 These and other features are described in 60 the following specification and illustrated in the accompanying drawing, in which

Fig. 1 is a perspective view, with a section broken away, of the completed tree,

Fig. 2 is a side elevation of a shoe having 65 our novel tree inserted therein, and

Figs. 3 and 4 are enlarged details.

The toe piece 10 of the tree is made of sheet celluloid, which adapts itself particularly well for the purpose because of the ease with 70 which it may be cut and formed and because of the many attractive colors and surface designs in which the material may be produced. This toe piece 10 is provided with inturned bottom flanges 12 of curved contour so that they will not interfere with the insertion or removal of the tree from a shoe and in order to make the tree slightly more rigid at the forward portion of the toe piece, a narrow inturned bottom flange 14 is provided which extends around the toe piece. It is possible by 75 a variety of methods well understood in the art to form such toe pieces over wooden lasts or the like so that they may assume the exact contour desired to make the tree best adapted for fitting any particular form or size of shoe.

80 Preferably the trees are made in a variety of sizes by varying the dimensions of the toe pieces and the length of the heel pieces. In

85 order to limit the flexibility of the toe piece at the ball of the shoe, a rigid bridge member 16 is secured to the inturned flanges 12 by means of rivets 18 passing through short slots 90 in the flanges 12. It will be understood 95 that these rivets are not headed tightly against the material but that a certain amount of slippage is allowed so that the natural resilience of the toe piece will bring it into close engagement with the inside of a shoe in which it is inserted. This bridge member 16 pro-

vides for the attachment of a heel piece 22 to the toe piece 10 and to this end the bridge member is provided with an upturned U-shaped intermediate portion 24 at a suitable point in which there is provided a cross-bar 26 serving as a pivot for the forward end of the heel piece. The heel piece is preferably constructed of a strip of spring metal 28 such as steel formed into a small loop 30 at its forward end surrounding the cross-bar 26. This small loop is so formed with relation to the spring member 28 that the center of the loop is in line with the length of the spring member. At the other end of the heel piece the spring member 28 is formed into a larger loop 32 the center of which is also in line with the length of the heel piece and has a diameter equal to substantially twice the distance between the cross-bar 26 and the bottom of the toe piece. This arrangement results in holding the toe piece firmly against the bottom of a shoe when it is flexed in use so that it assumes the position illustrated in Fig. 2 with the heel piece acting as a thrust spring between the heel end of the shoe and the toe piece. This not only holds the toe piece against the bottom of the shoe but tends to stretch the shoe to its normal form and thereby to assist in maintaining the shape of the shoe when it is not upon the foot of the wearer.

We have found that the appearance and utility of our novel shoe tree may be greatly improved by providing a cover member 34 of a material having different characteristics from those of the spring metal heel piece, said material being similar to that used for the construction of the toe piece 10 so that it will blend therewith. In one desirable embodiment, as illustrated, the cover 34 is made of sheet celluloid matching the celluloid used in constructing the toe piece 10. Such a cover will have ample flexibility but less resilience than the spring metal of the heel piece and will be non-oxidizable. It will therefore avoid rusting of the steel piece and will protect the shoe from stains due to such rust. This cover member is bent around the loop 32 of the outer end of the heel piece and its end is secured rigidly to the heel piece by means of a rivet 36. This rivet passes through two thicknesses of the sheet metal strip 28 and an interposed end 38 of the cover. The cover then extends along the top of the heel piece in closely superposed relation and is secured at intervals by rivets 40, 42 and 44. Preferably, in order to facilitate the assembling of the tree in the course of its manufacture, the hole through which the rivet 40 passes is slightly elongated in order that there may be no difficulty in inserting this rivet because of a lack of registration between the hole in the cover and the hole in the spring piece 28.

We have discovered that it is highly important that provision be made for relative slippage between the cover 34 and the metal

strip 28 in order to permit the repeated flexure of the heel piece without destroying the cover or at least disengaging it from the spring strip. To this end, a slot 46 is provided at the inner or forward end of the cover 34 of the heel piece for the passage of the rivet 44. In the position of the heel piece illustrated in Fig. 1 this slot extends forwardly of the rivet but when the heel piece is flexed, as illustrated in Fig. 2, then the cover is drawn toward the rear relatively to the spring piece 28 so that the slot is largely back of the rivet 44 instead of in front of it. Preferably and chiefly in order further to improve the appearance of the tree, the rivet 44 has a head of considerable size so that most of the slot 46 is concealed in either position of the tree. A similar slot 48 is provided for the passage of the rivet 44 but, because of the difference in the distance between said rivet 42 and the loop 32 of the heel piece, the slot 48 needs only to be approximately half as long as the slot 46. It will be understood that the rivet 42 is of assistance in keeping the cover 34 in engagement with the spring strip 28 when after a considerable period of flexure of the heel piece the latter is again extended into the position shown in Fig. 1. under some conditions of use and temperature there may be a tendency for the cover to retain its curvature instead of being straightened out with the spring member 28. This is entirely prevented, however, by the rivet 42 so that the cover is always kept in close contact with the upper side of the spring strip 28.

It has been found advantageous, too, to provide a reinforcement 50 adjacent to the middle of the heel spring to prevent undue bending of the heel spring to an extent sufficient to give the latter a permanent set. It is to be understood that, although the strip of spring metal 28 is so designed that, without being unduly heavy, it has sufficient strength and resilience to withstand ordinary use, said strip is slightly weakened by the presence of the rivet hole adjacent to its center for the rivet 42. This resultant weakening is just enough so that a heel piece without the reinforcement 50 can be accidentally or intentionally bent to such an angle that it retains its set and thereby not only is ruined in appearance but is also rendered unfit for use. We have accordingly provided this reinforcement 50, which preferably is formed as a circular piece of thin sheet metal to avoid the need of turning it to any particular position in assembling, and have secured it to the under side of the heel spring by the rivet 42 used for holding the central portion of the cover 34. The diameter of this reinforcement is approximately equal to the width of the heel spring 28 and the rivet 42 is clenched loosely, not only to allow slippage of the central part of the cover 34

but also to hold the reinforcement in such a position that it contacts with the under side of the heel spring 28 only at its forward and backward edges as said spring is flexed. 5 This so distributes the strain of the bending of the heel piece that it is practically impossible to bend the heel piece manually so sharply that it will retain its set.

The use of the device will be apparent from 10 the illustration but it should be noted that the tendency of the spring of the heel piece is not only to thrust the toe piece into position within the toe of the shoe and against the bottom of the sole but further that the tendency 15 is to thrust the looped end 32 of the heel piece into the bottom corner of the rear end of the shoe, and improved action of the tree in maintaining the shape of the shoe is thereby effected.

20 Having thus described the invention, what we claim as new and desire to secure by Letters Patent of the United States is:

1. In a shoe tree, a toe piece, a resilient heel piece formed of flat spring metal, and a 25 decorative protective covering of sheet celluloid for said heel piece rigidly secured to said heel piece adjacent to one end thereof and slidably secured to said heel piece adjacent to the other end thereof.

30 2. In a shoe tree, a toe piece, a resilient heel piece connected to said toe piece comprising a strip of resilient metal, and a decorative non-metallic cover for said heel piece overlying the shoe engaging end thereof riveted to said resilient strip at intervals, provision being made for slippage between certain of said rivets and the cover strip.

35 3. In a shoe tree, a toe piece, a resilient spring metal heel piece connected to said toe piece adapted to be tensioned by bending the heel piece between said toe piece and the heel end of a shoe in which the tree is inserted to thrust the toe piece into the shoe, and a cover of sheet celluloid attached to said heel piece at intervals, said cover being firmly attached to the heel piece at the heel end and provided with slots of varying lengths adjacent to said attaching means to allow slippage between the forward end of the cover and the heel piece as the covered heel piece is flexed.

40 4. In a shoe tree, a celluloid toe piece and a resilient heel piece connected to said toe piece adapted to be tensioned between said toe piece and the heel end of a shoe in which the tree is placed to thrust the toe piece into the shoe, and a cover of sheet celluloid loosely riveted to said heel piece at intervals, said cover being provided with slots of varying lengths adjacent to said attaching means to allow slippage between the cover and the heel piece as the covered heel piece is flexed, the slot adjacent to an end of the heel piece being longer than the slot at an intermediate point in said heel piece.

45 5. In a shoe tree, a toe piece and a resilient

heel piece connected to said toe piece having a looped outer end, said heel piece being provided with a cover of flexible material, the end of which is interposed between two parts of the looped end and secured to said looped end by means of a fastening member, passing through the end of the cover and said heel piece. 70

6. In a shoe tree, a toe piece and a resilient heel piece connected to said toe piece having a looped outer end, said heel piece being provided with a cover of flexible material, the end of which is interposed between two parts of the looped end and held by means of a fastening member extending through the end of the cover and arranged to hold the loop of the heel piece in curved relation. 75

7. In a shoe tree, a toe piece, a resilient heel piece connected to said toe piece formed of flat spring metal, said heel piece being bent to form a loop at its outer end, and a cover for said heel piece, the end of which is interposed between the end of the loop and the body of the heel piece, and is secured in that position by a fastening member which passes through the end of the cover and two thicknesses of the looped heel piece, said cover extending over the outer end of said fastening member and along said upper surface, and means for securing said cover to the heel piece at another point adjacent to the other end of the heel piece. 85 90

8. In a shoe tree, a hollow toe piece comprising a resilient curved upper portion having inturned bottom flanges, a rigid bridge member loosely secured to said flanges to allow the resilience of the toe piece to be effective in expanding the sides of its curved upper portion against the inside of the shoe, and a heel piece connected to said bridge member. 100

9. In a shoe tree, a resilient heel piece comprising a strip of resilient material, a cover for said heel piece secured to said resilient strip at intervals, and a reinforcing device secured to the under side of said heel piece at an intermediate point constructed and arranged to prevent undue bending of the heel piece. 105 110

10. In a shoe tree, a resilient heel piece comprising a strip of resilient material, a cover for said heel piece, attaching means for securing said cover to said heel piece at intervals, one of said attaching means being located near the center of the heel piece, and a reinforcement secured to said heel piece by 115 said last-mentioned attaching means.

11. In a shoe tree, a toe piece, a resilient heel piece connected to said toe piece comprising a strip of resilient material, a cover for said heel piece riveted to said resilient strip at intervals, provision being made for slippage between certain of said rivets and the cover strip, one of said rivets being located at an intermediate point in the length of the heel piece, and a circular reinforce- 125 130

ment secured to the under side of said heel piece by said last-mentioned rivet which rivet is loosely clenched to allow slippage as aforesaid and to permit the reinforcement to contact at its edges with the heel piece as the latter is bent.

In testimony whereof we have signed our names to this specification.

SEXTUS A. EDDINS.
